UNITED STATES PATENT OFFICE.

CHARLES A. FETTERS, OF NEW YORK, N. Y., ASSIGNOR TO SANITARY SECTIONAL BRUSH COMPANY, OF NEW YORK, N. Y., A CORPORATION OF NEW YORK.

SECTIONAL HAIR-BRUSH.

No. 873,852.

Specification of Letters Patent.

Patented Dec. 17, 1907.

Application filed March 2, 1907. Serial No. 360,236.

To all whom it may concern:

Be it known that I, CHARLES A. FETTERS, a citizen of the United States, of New York, county of New York, and State of New York, have invented certain new and useful Improvements in Sectional Hair-Brushes, fully described and represented in the following specification and the accompanying drawings, forming a part of the same.

10 This invention is a modification of that shown in my application No. 230,448 filed October 24, 1904 for patent on sectional brush, and its object is to simplify the construction so as to reduce in the greatest degree the number of pieces in the brush which require to be cleansed, and the work of separating the sections.

In this class of brush, the brush-block is formed wholly of detachable strips having 20 each a single row of bristle-tufts thereon, so that when the strips are separated from one another each row of bristle-tufts may be readily cleansed by washing and scrubbing, because accessible upon both sides.

25 The strips are made of uniform cross section and provided with corresponding tongues and grooves upon their opposite edges, so that they may be all manufactured in long bars by a uniform process and then 30 cut into portions or strips of graduated length to form a brush-block of oval or rounded contour. Such mode of manufacture permits brushes of various sizes, forms and contour to be made all from the same 35 kind of strips, and it permits, when desired, the tufting of the long strips before cutting up into sections of graduated length, and thus greatly cheapens the manufacture of the brush as the tufts can be inserted by 40 automatic machinery with much greater rapidity and correspondingly less expense than if inserted in the brush-block.

In addition to the tongues and grooves which form the tufted strips in alinement 45 when assembled, means is required in the finished brush for holding the strips from longitudinal movement or displacement, and also means for clamping the strips detachably together. Such means operates prefer- 50 ably upon the opposite outer strips of the block so as to clamp the other strips between the same. When a handle is required upon the brush, it may be formed integral with

the middle section or strip, and the addition of a handle does not therefore increase 55 the number of pieces in the brush.

The handle is generally of greater width than a single tufted strip, and its width may be extended by gluing portions of the tongued and grooved strips upon its opposite sides to the desired width and then trimming the same to the desired shape. The center strip of the brush and the handle would be formed of strips before any tuft-holes were drilled in the strips, thus making 60 the handle free from any such holes. In the construction illustrated, I have shown a straight rod or bolt extended through the sections to prevent longitudinal displacement, and a spring-clip for clamping the sec- 65 tions together.

In my Patent No. 805,431 dated November 21, 1905, which is a division of the said application No. 230,648, I have shown a bolt extended through the sections with a 75 head upon one end and a nut upon the other, to perform the double function of holding the strips from displacement when clamping them together, but the bolt illustrated herein has no head and nut to operate as a clamp.

In the drawing, Figure 1 shows an oval brush-block for a so-called "army" and "navy" brush with a portion of the strips separated to show their detachable nature, a bolt extended through the strips and a 80 spring-clip indicated in dotted lines. Fig. 2 illustrates a brush with a handle having the spring-clip placed on the back of the brush and the clip-jaws embracing the outer strips. Fig. 3 represents the end of the brush-block 85 in Fig. 1 or Fig. 2, with the spring-clip thereon. Fig. 4 is a perspective view of the spring-clip; and Fig. 5 is a cross section of the handle and its greatest width upon the brush in Fig. 2.

a designates the separable strips each containing one row of holes *b* for the bristle-tufts *b'*, and each provided upon its opposite edges with a tongue *c* and groove *d* to hold the sections in alinement.

A transverse hole *f* is extended across each section at the middle of its length, and a bolt *e* without head or nut is shown extended through the holes so that the strips can be strung thereon from clamping together, or 105 slipped off as indicated at the right side of

Fig. 1, when it is desired to wash and cleanse the bristles.

As each strip has only one row of the bristle-tufts, the tufts are accessible upon both sides and can be washed and cleansed with great ease and completeness.

The spring clip, adapted to clamp the outer edges of the brush-block, is shown in Fig. 4 consisting of a flat plate *g* having jaws *h* at the opposite ends, the plate being adapted as shown in Fig. 2 to lie across the back of the brush-block and the jaws to embrace the edges of the opposite outer sections as shown in Fig. 3, and to be held thereon by the elastic clamping pressure of the jaws. The clip is indicated in dotted lines in Fig. 1 to show its relation to the sections or strips of that brush-block when assembled.

The bolt *e* is shown in dotted lines in Fig. 2, and as also in Fig. 1, except where exposed between parts of the separated strips. The brush-block is shown in Fig. 2 with a handle extended from the middle strip, the handle being shown formed as indicated in Fig. 5 by gluing similar tongued and grooved strips at the sides of such middle strip to secure the desired width, the edges of such supplemental strips being cut out and the edges rounded as indicated in Fig. 5 to form the handle.

It will be readily seen that the strips *a* can be formed by suitable machinery of any desired length and then cut up into pieces, to form the side portions of graduated length which are required for a brush of oval or rounded contour, and such long strips may, if desired, be tufted before they are cut into the desired sections. By this process of manufacture, the strips may be cut to form a brush-block of any desired length or width, and the same machinery and processes may thus be used for preparing the material to make all kinds of brushes.

In a brush having a handle, it is immaterial so far as the brush-block is concerned, whether the handle be formed of a plurality of tongued and grooved strips as shown in Fig. 2, or be made of a single wide piece integral with the strip for the middle of the brush-block.

In the practical use of the brush, the clamping means is disengaged when it is desired to cleanse the bristles and the tufted strips are then readily separated and thrown into a bowl of water with suitable disinfecting material.

As each strip possesses only a single row of bristle-tufts they may be scrubbed and cleansed far more thoroughly than where two or more rows are contiguous, and when suitably cleansed and dried the strips are readily re-assembled and the clamping means re-applied to hold them in their working relation.

It is obviously immaterial whether sepa-

rate means as the bolt *f* and clamp *g* be used for holding the strips from longitudinal displacement and clamping them together, as shown in the Fig. 2 of the drawing, or a single agency be used to perform both functions, 70 as with the bolt and nut shown in my Patent No. 805,431.

Having thus set forth the nature of the invention what is claimed herein is:

1. A brush-block wholly divided into 75 straight longitudinal strips, each strip being provided with a row of bristle-tufts and the strips all having parallel edges with tongue and groove connections upon the adjacent edges for holding the strips in alinement, 80 means for holding the strips from longitudinal movement when assembled, and means for clamping the strips detachably together for conjoint use, the sides and ends of the strips upon the edges of the block being 85 trimmed to the contour desired.

2. A brush having the entire brush-block divided into straight longitudinal strips, each strip being provided with a row of bristle-tufts and the strips all having parallel 90 edges and formed with a groove upon one edge and an integral corresponding rib upon the opposite edge for holding the strips in alinement, a rod extended through the strips to prevent longitudinal movement, and 95 means operating upon the opposite outer strips of the block for clamping the strips together.

3. A brush having the entire brush-block divided into straight longitudinal strips, 100 each strip being provided with a row of bristle-tufts and the strips all having parallel edges with a groove upon one edge and an integral corresponding rib upon the opposite edge for holding the strips in alinement, 105 means for holding the strips from longitudinal movement when assembled, means operating upon the opposite outer strips of the block for clamping the strips together, and a handle connected with the middle strip at 110 one end of the block.

4. A brush having the entire brush-block divided into straight longitudinal strips, each strip being provided with a row of bristle-tufts and the strips all having parallel 115 edges with a groove upon one edge and an integral corresponding rib upon the opposite edge for holding the strips in alinement, means for holding the strips from longitudinal movement when assembled, means operating upon the opposite outer strips of the block for clamping the strips together, and a handle connected with the middle strip at 120 one end of the block and having tongued and grooved strips like the strips of the block, 125 glued together and rounded to form said handle.

5. A brush having the entire brush-block divided into straight longitudinal sections of graduated length to form an oval brush- 130

block, each section being provided with a row of bristle-tufts, and the sections all having parallel edges to facilitate their manufacture in long strips with a groove upon one edge 5 and an integral corresponding rib upon the opposite edge for holding the strips in alignment when assembled, a rod extended through the strips to prevent longitudinal movement, and a spring-clamp with jaws at 10 opposite ends fitted to the opposite outer

strips of the block for clamping the strips together.

In testimony whereof I have hereunto set my hand in the presence of two subscribing witnesses.

CHARLES A. FETTERS.
